Patented Sept. 9, 1919.

UNITED STATES PATENT OFFICE.

ROBERT MIEHLE, OF CHICAGO, ILLINOIS.

TRIPPING MECHANISM FOR PRINTING-PRESSES.

1,315,382.

Specification of Letters Patent.

Patented Sept. 9, 1919.

Application filed November 30, 1917. Serial No. 204,720.

To all whom it may concern:

Be it known that I, ROBERT MIEHLE, a citizen of the United States, residing at Chicago, in the county of Cook and State of Illinois, have invented a certain new and useful Improvement in Tripping Mechanisms for Printing-Presses, of which the following is a full, clear, concise, and exact description, reference being had to the accompanying drawings, forming a part of this specification.

My invention relates to tripping mechanism for printing presses and the like and has for its general object to provide tripping mechanism which is controlled by the passage of a sheet through the machine, said sheet acting upon mechanism to prevent the tripping mechanism from operating so that the sheet may be brought into impression relation with the printing element of the machine.

Another object resides in providing a construction, arrangement, and combination of elements whereby the sheet imparts sufficient motion to a movable element and imparts sufficient force thereto to enable the movable element to actuate the devices hereinafter described or any devices as may be desired without requiring a delicate construction and adjustment of parts, and whereby the possibility of the sheet being torn or ruptured is very remote, and preferably whereby the sheet is held firmly against movement caused by the action of the movable element thereagainst. This last mentioned feature is of considerable importance as I contemplate using the invention to control the tripping mechanism of the second printing couple of a two color flat bed printing press and engaging the sheet to control the same after the first printing operation has been effected as the proper time for actuating the trip control mechanism of the second couple occurs as the sheet is being transferred from the first couple to the second couple.

A further object resides in providing means for controlling the trip control mechanism, which is independent of the above noted sheet operated means, this independent means being adapted to control said trip control mechanism to effect the tripping of the printing couple and to render the same ineffective to trip independently of the sheet operated means.

With these and other objects in view

which will be hereinafter described and particularly pointed out in the claims, the invention consists in the mechanism illustrated in the accompanying drawings, forming a part of this specification, in which:

Figure 1 is a partial side elevation of a two couple printing machine embodying my invention, the machine illustrated being a "two-color" machine, or one which is adapted to print twice upon the same side of the sheet.

Fig. 2 is a partial side elevation of the machine taken on the opposite side of the machine.

Fig. 3 is a partial sectional view in rear elevation upon the line 3 3 of Fig. 1.

Fig. 4 is a view similar to Fig. 1 showing the parts in a different position in the cycle of operation.

Fig. 5 is a side elevation in partial section of a portion of the mechanism showing the same in another position.

Fig. 6 is a partial side elevation of another portion of the mechanism showing the same in the same relative position as Fig. 5.

Fig. 7 is a plan view of a portion of the mechanism on the line 6 6 of Fig. 4.

Fig. 8 is a sectional elevation of a portion of the mechanism on the line 8 8 of Fig. 4.

Like characters of reference indicate like parts in the various views.

In the drawings 1 designates the frame of the machine in which is journaled the first impression cylinder 2, the transfer cylinder 3, and the second impression cylinder 4. The impression cylinder 2 rotates in a counter clockwise direction, the transfer cylinder 3 rotates in a clockwise direction, the impression cylinder 4 rotates in a counter clockwise direction. The bed 5, which carries a form 6 for the first impression cylinder 2 and a form 7 for the second impression cylinder 4 is reciprocated in unison with the cylinders as is the usual practice. The cylinder 2 is provided with grippers 8 which are adapted to take a sheet from a feed board 9, bring the same in impression relation with the form 6, and then to transfer the sheet to the grippers 10 of the transfer cylinder 3 which carries the sheet during nearly one and one-half revolution of its movement. The grippers 11 of the cylinder 4 which take the sheet and bring the same into impression relation with the form 7 after which said grippers release the sheet onto a delivery apparatus, not shown, as is

the usual practice. The usual mechanism is employed for opening and closing the grippers, the same being timed so that the grippers 8 close upon a sheet, positioned upon the feed board 9, pass the same through the line passing through the axes of the cylinders 2 and 3, said grippers opening when they reach a point adjacent said line on the next revolution of said impression cylinder 2 to release the sheet, at which point the grippers 10 of the transfer cylinder 3 close upon the sheet and carry the same past the line joining the axes of cylinders 3 and 4. The sheet is carried upon the transfer cylinder 3 for nearly one and one-half revolution, and when the grippers 10 reach a point adjacent said line joining the centers of cylinders 3 and 4 they are opened to release the sheet, at which point the grippers 11 are closed upon the sheet.

The impression cylinders 2 and 4 are adapted for movement transversely of their axes to move the same into and out of printing relation with their respective forms, the said cylinders being journaled in boxes 12 which are slidably mounted in guide-ways 13 of the press frame 1. These boxes 12 are provided with springs 14 which are adapted to move said boxes to position the impression cylinders in their non-impression or tripped positions. The boxes 12 are also provided with eccentric mechanisms 15 of usual construction whereby the impression cylinders may be moved into impression relation with their respective forms against the influence of the springs 14, said eccentric mechanisms being provided with actuating arms 16 whereby the same may be moved.

The tripping mechanism as shown is of usual construction and is fully described in the United States Patent No. 1,081,320, granted to me December 16, 1913, and needs but a cursory description in order that this invention may be fully understood. A separate tripping mechanism is employed for each of the impression cylinders 2 and 4, and as they are generally similar in construction similar characters of reference will be applied to the corresponding parts of both. A cam shaft 17 is journaled in the press frame and is driven from the press mechanism and makes one revolution for each cycle of the machine. A rock shaft 18 is journaled in the press frame and has a cam arm 19 affixed thereto, which is provided with a friction roller which is engaged in the groove of a cam 20 mounted upon said cam shaft 17. The cam arm 19 is rotatably mounted upon said rock shaft 18 and carries a hook 21 pivotally mounted at its outer end, which is adapted to engage the tooth 22 fixedly mounted upon said rock shaft 18. Arms 23 are mounted upon said rock shaft 18 on either side of the machine and are connected with their respective actuating arms 16

through connecting links 24, and the eccentric mechanisms are actuated to move the impression cylinder into and out of impression position by the cam 20 acting through the cam arm 19, hook 21, tooth 22, arms 23, and the connecting links 24 which are connected to said actuating arms 16. The hook 21 is pivotally mounted upon the cam arm 19 and is adapted to be moved out of engagement with the tooth 22. A roller 25 is mounted upon a hook 21 near the free end thereof and travels in the groove of a cam lever 26 which is fixedly mounted upon a rock shaft 27 journaled in the press frame. The upwardly facing surface of the cam groove of the cam lever 26 is provided with a raised portion 28, which lies below the roller 25 when the roller of the cam arm 19 is passing through the arc *a b* of the cam 20, the mechanism being so arranged that when said roller of the cam arm 19 is passing through said arc *a b* the impression cylinder is in its upper or tripped position. If the cam lever 26 is raised, while the parts are in this position, the raised portion 28 engages the roller 25 to lift the hook 21 out of engagement with the tooth 22, thus disconnecting the cam arm 19 from the eccentric mechanisms 15 whereby the cylinder remains in its upper or tripped position during the succeeding revolution of the cam 20. If the cam lever 26 is released during the time that the roller of the cam arm 19 is passing through that portion of the groove of the cam 20 which lies in the arc *b c, b d*, and *b a*, said cam lever and the hook 21 are supported by the engagement of the under surface of the hook, which lies between the hook portion thereof and the roller of the cam arm 19, with the crown of the tooth 22, the tooth receiving portion of said hook having passed out of engaging relation with said tooth during the initial movement of the roller of cam arm 19 through the arc *b c*. If said cam lever 26 is released during said period the hook reengages the tooth as said roller of the cam arm 19 passes through the arc *a b* of the cam 20 after having passed through said arc *d a*, whereupon the normal position of the parts is again resumed. It will be noted that while the roller of the cam arm 19 is passing through the arc *b d* the cylinder is in impression relation with its form.

The mechanism just described is duplicated in the tripping mechanism for each impression cylinder, or printing couple, the only difference in construction between the tripping mechanism of each couple lying in the means for controlling the same, or in the means for positioning the cam lever 26 to control the position of the hook 21 relative to the tooth 22. The rock shaft 27 of the first couple, which includes the impression cylinder 2, has an arm 29 fixedly mounted thereon. The free end of this arm 130

is connected to the foot treadle of usual construction, not shown, whereby the cam lever 26 of said first couple may be manually positioned to trip the impression cylinder 2. 5 Inasmuch as the means for tripping the first couple, or the impression cylinder 2, does not enter into this invention, it needs no further description. The rock shaft 27 of the second couple has an arm 30 fixedly 10 mounted thereon, and which by reason of this fixed connection with said rock shaft is adapted to control the position of the cam lever 26. A tension spring 31 has its opposite ends connected to said arm 30 and the 15 press frame 1, and is adapted to normally maintain said arm in its upper position and said cam lever 26 in its lower position with the downwardly facing surface of the cam groove of said cam lever engaged with the 20 roller 25, which roller, it will be noted, is limited in its downward movement by the engagement of the bottom of the hooked portion of the hook 21 with the crown of the tooth 22. The upward movement of the arm 25 30 is also limited by this engagement. A cam 32 is mounted upon the cam shaft 17 of the first couple and it is engaged by a roller 33 journaled upon the free end of a lever 34, which is pivoted upon the rock shaft 27 of 30 the second couple. A tension spring 35 has its opposite ends connected to said lever 34 and the press frame 1 and maintains said roller 33 in engagement with the cam 32. A coupler 36 is pivoted at the free end of the 35 arm 30 and has an upwardly facing surface formed at the free end thereof which is adapted to engage a downwardly facing surface 37 formed on an extension 38 of the lever 34, when the arm 30 is in its upper 40 position, and the lever 34 is in its upper position with the roller 33 thereof in engagement with the low portion of the cam 32. Mounted upon extension arms of the press frame 1 is a stationary rod 39 which 45 extends across the machine and is disposed adjacent the transfer cylinder 3 just above the point where the periphery of the cylinder 3 and the cylinder 4 nearly meet. The rod 39 carries bearing brackets 40 mounted 50 thereon at intervals throughout its length, and the rock shaft 41 is journaled in said bearing brackets and the extension arms of the press frame which support said stationary rod 39. An arm 42 is mounted upon 55 the end of the rock shaft 41 which lies directly above the coupler 36, and the upper end of a connecting rod 43 is pivotally mounted at the free end thereof. The coupler 36 has a horizontally extending arm 60 44 formed thereon, and the lower end of the connecting rod 43 is pivotally mounted at the free end thereof.

As is usual circumferential spacing members 45 are formed upon the surface of the 65 transfer cylinder 3 at intervals along the

length of the same. These are formed with outwardly projecting teeth for engagement with the sheet so that the printed matter on the sheet, which it will be noted is on that side of the sheet facing the surface of the 70 cylinder 3, is not marred. Gripper stops 46 are disposed within a recess of the cylinder 3, and the grippers 10 are adapted to clamp the leading edge of the sheet upon said gripper stops. The engaging surface of said 75 gripper stops is disposed in the same plane as the sheet engaging surface of the spacing members, and the leading ends of said spacing members are disposed in line with said gripper stops whereby the leading edge 80 of the sheet is supported and held in a very rigid manner. Mounted upon the rock shaft 41 is an arm 47 which has a broad engaging blade 48 formed at the free end thereof. The arm 47 is so disposed that when it is in 85 its lower position the blade 48 thereof projects into the space between the sheet, supported as herein before described, and the periphery of the cylinder and projects across the path of the sheet. The main portion of this blade is disposed between a pair of gripper stops and the ends thereof extend beyond said gripper stops to engage the sheet on the other side thereof beyond the space members adjacent the gripper 90 stops, and has slots 49 formed in the transverse edge thereof and so disposed that the spacing members, grippers, and gripper stops 46 in line with said blade pass through said slots when the blade is in its lower position. The slots 49 which are disposed in line with the grippers are cut deeper so that the gripping portions of the grippers which project above the surface of a held sheet 95 may pass said blade in all positions of said blade and grippers without interference. The above described parts are so arranged that when the couple member 36 is positioned so that the upwardly facing surface thereof is in line with the downwardly facing surface 37 of the extension 38 the arm 42 is in 100 its lower position, and when said couple member is positioned so that the upwardly facing surface thereof is out of line with said downwardly facing surface of the extension 38 said arm 42 is in its upper position. When the arm 42 is in its lower position the blade 48 projects into the space between the sheet and the cylinder 3 and across the path thereof, and when said arm 110 is in its upper position the transverse edge of the blade is positioned to pass over the outer surface of the sheet supported upon said cylinder 3. The pivotal connection between the arm 44 and the connecting rod 120 43 is so disposed that when the couple member 36 is positioned so that the upwardly facing surface thereof underlies the downwardly facing surface 37, the center of said pivotal connection is coaxial with the rock 125 130

shaft 27 of the tripping mechanism of the second couple, so that as the cam 32 moves the mechanism as will be hereinafter described, the rock shaft 41 is not disturbed.

5 As before stated the cam lever 26 is operable only to position the tripping mechanism when the roller of the cam arm 19 is passing through the arc *a b*, and the cam 32 is so timed, relative to the cam 20 of the second couple, that the high portion thereof will engage the roller 33 of the lever 34 as the roller of the cam arm 19 is passing through said arc.

In the operation of the device the upwardly facing surface of the couple member 36 normally underlies the downwardly facing surface 37 to maintain an operable connection between the lever 34 and the arm 30. In this position the blade 48 projects 15 across the path of a sheet carried by the transverse cylinder 3, see Figs. 4, 5, and 6. As the press is operated the roller 33 is engaged by the high portion of the cam 32 to move the same downwardly during each 20 cycle. This movement is transmitted to the couple member 36 and the arm 30 to the cam lever 26, which is raised to engage the raised portion 28 thereof with the roller 25. As before stated this movement occurs at the 25 time when the roller of the cam arm 19 is passing through the arc *a b* of the cam 20, and as a result the hook 21 is lifted out of engagement with the tooth 22 and the tripping mechanism is positioned to trip said cylinder. The gravitational tendency of the parts 30 connected with the couple member 36 for moving the same relative to the extension 38 serves to normally retain the same in engagement with said extension, and a counterweight 50 is formed upon said couple member to almost counterbalance this gravitational 35 tendency so that undue strain will not be put upon the sheet as it engages the blade 48 to move said couple member 36 out of engagement with said extension 38.

The upwardly facing surface of the couple member 36 is disposed relative to the downwardly facing surface 37 of the extension 38 that when the roller 33 of the lever 34 40 is engaged with the low portion of the cam 32, clearance is left between said opposing surfaces so that said couple member may be easily operated.

When a sheet is transferred from the impression cylinder 2 to the impression cylinder 4 by said transfer cylinder 3 the same 45 engages said blade 48 to move said couple member out of engagement with the extension 38 as before described, and the blade 48 50 is so positioned that the leading edge of the sheet will engage the same to move the couple member 36 just previous to the time when the roller 33 of the lever 34 is engaged by the active part of the cam 32 to move

the same downwardly. This operates to prevent the cam 32 from positioning the cam lever 26 of the second couple to position the tripping mechanism to trip the second couple. Figs. 5 and 6 show the mechanism in position to trip at the point where, if a sheet were passing through the machine, the couple members 36 would be moved to prevent the cam 32 from positioning the tripping mechanism to trip that couple. Fig. 1 shows the roller 33 in engagement with the high portion of the cam 32 from positioning the tripping mechanism to trip that couple. Fig. 1 also shows the roller 33 in engagement with the high portion of the cam 32 with the couple member moved out of engagement with said extension 38 by a sheet 51 supported on said transfer cylinder 3.

Thus it will be noted that I have provided means for controlling the tripping mechanism by the passage of a sheet through the machine, the nature and construction being such that enough movement is imparted to the mechanism to properly operate the same without injury to the sheet.

In addition to the above described mechanism I provide means for independently controlling the trip positioning means whereby the tripping mechanism may be controlled to trip the cylinder or to maintain the same in printing relation with its form regardless of whether or not a sheet is passing through the machine. This mechanism consists in the following. Pivoted upon the free end of the arm 30, and preferably coaxial with the couple member 36, is a second coupler element 52 which has a hook formation adapted to underlie the extension 38. An operating arm 53 is formed upon said coupler element 52 and has a slide rod 54 pivotally connected to the free end thereof. The slide rod 54 has an enlarged end portion formed with a longitudinal slot 55 which is engaged by stud 56 mounted on the press frame 1, and an operating handle 57 is formed upon the extending end of said enlarged portion. The slot 55 is formed with three transverse slots 58 which are disposed upon the upper side thereof. When the center transverse slot is in engagement with the stud 56 the couple member 52 is out of engaging relation with the extension 38, and when the outer transverse slot is engaged with said stud said couple member underlies said extension 38 so that when the cam 32 operates lever 34 to move the same downwardly motion will be transmitted to said couple member 52 to the arm 30 and the tripping mechanism will be positioned to trip the couple as before described.

A stud 59 is formed upon an extension member of the couple member 52 and is adapted to engage the couple member 36 to

move the same out of engaging relation with the extension 38 when the inner transverse slot is engaged with the stud 56.

While I have herein shown and particularly described the preferred embodiment of my invention I do not wish to be limited to the precise details of construction shown as changes may readily be made without departing from the spirit of my invention, but 10 having thus described my invention I claim and desire to secure by Letters Patent the following:

1. In a printing press, the combination with a sheet carrying cylinder adapted to receive a sheet and to carry the same, spaced gripper stops on said cylinder adapted to position the leading edge of the sheet in spaced relation with the periphery of the cylinder, spaced grippers adapted to engage 15 the leading edge of the sheet and to clamp the same on said gripper stops, and a movable element adapted to project into the space between the leading edge of the sheet, and the periphery of the cylinder and across 20 the path of the sheet between the gripper stops and adapted to be engaged by the leading edge of the sheet to be moved thereby.

2. In a printing press, the combination with a sheet carrying cylinder adapted to receive a sheet and to carry the same, spaced gripper stops on said cylinder adapted to position the leading edge of the sheet in spaced relation with the periphery of the cylinder, spaced grippers adapted to engage 30 the leading edge of the sheet and to clamp the same on said gripper stops, and a movable element extending across said grippers and gripper stops and adapted to project into the space between the leading edge of 35 the sheet and the periphery of the cylinder and across the path of the sheet and having slots formed at the projecting portion thereof in registry with the several grippers and gripper stops and adapted to be engaged by the leading edge of the sheet to be moved 40 thereby.

3. In a printing press the combination with a sheet carrying cylinder adapted to receive a sheet and to carry the same, spaced gripper stops on said cylinder adapted to position the leading edge of the sheet in spaced relation with the periphery of the cylinder, spaced grippers adapted to engage 50 the leading edge of the sheet and to clamp the same on said gripper stops, circumferential spacing members disposed at intervals along the length of the cylinder adapted to hold the sheet in spaced relation with the periphery of said cylinder, and a movable element adapted to project into the space between the sheet and the periphery of the cylinder and across the path of the sheet between several gripper stops and several spacing members and adapted to be engaged by 55 the sheet to be moved thereby.

4. In a printing press, the combination with a sheet carrying cylinder adapted to receive a sheet and to carry the same, circumferential spacing members disposed at intervals along the length of said cylinder 70 adapted to hold the sheet in spaced relation with the periphery of said cylinder, means for holding the sheet on said cylinder, and a movable element extending across said spacing members and adapted to project into the space between the sheet and the periphery of the cylinder and across the path of the sheet and having slots formed at the projecting portion thereof in registry with the several spacing members and adapted to be engaged by the sheet and to be moved 75 thereby.

5. In a printing press, the combination with a sheet carrying cylinder adapted to receive a sheet and to carry the same, circumferential spacing members disposed at intervals along the length of said cylinder adapted to hold the sheet in spaced relation with the periphery of said cylinder, spaced gripper stops on said cylinder adapted to 80 position the leading edge of said sheet in spaced relation with the periphery of said cylinder, spaced grippers adapted to engage the leading edge of the sheet and to clamp the same on said gripper stops, said spacing 85 members supporting the leading edge of the sheet between said gripper stops, and a movable element extending across said spacing members and adapted to project into the space between the sheet and the periphery 90 of the cylinder and across the path of the sheet and having slots formed at the projecting portion thereof in registry with the several spacing members and gripper stops and adapted to be engaged by the leading 95 edge of the sheet to be moved thereby.

6. In a printing press, the combination with a sheet carrying cylinder adapted to receive a sheet and to carry the same, spaced gripper stops on said cylinder adapted to 100 position the leading edge of the sheet in spaced relation with the periphery of the cylinder, spaced grippers adapted to engage the leading edge of the sheet and to clamp the same on said gripper stops, a movable 105 element adapted to project into the space between the leading edge of the sheet and the periphery of the cylinder and across the path of the sheet between the gripper stops and adapted to be engaged by the leading 110 edge of the sheet to be moved thereby, tripping mechanism, means having operative connection with said tripping mechanism for controlling the same, and means included in said last mentioned means and having 115 operative connection with said movable element and adapted to be moved to render said controlling means ineffective to position said tripping mechanism to trip when said movable element is moved by the sheet. 125

7. In a printing press, the combination with a sheet carrying cylinder adapted to receive a sheet and to carry the same, spaced gripper stops on said cylinder adapted to position the leading edge of the sheet in spaced relation with the periphery of the cylinder, spaced grippers adapted to engage the leading edge of the sheet and to clamp the same on said gripper stops, a movable 10 element extending across said grippers and gripper stops and adapted to project into the space between the leading edge of the sheet and the periphery of the cylinder and across the path of the sheet and having slots 15 formed at the projecting portion thereof in registry with the several grippers and gripper stops and adapted to be engaged by the leading edge of the sheet to be moved thereby, tripping mechanism, means having operative connection with said tripping mechanism for controlling the same, and means included in said last mentioned means and having operative connection with said movable element and adapted to be moved to 20 render said controlling means ineffective to position said tripping mechanism to trip when said movable element is moved by the sheet. 25

8. In a printing press the combination with a sheet carrying cylinder adapted to receive a sheet and to carry the same, spaced gripper stops on said cylinder adapted to position the leading edge of the sheet in spaced relation with the periphery of the cylinder, spaced grippers adapted to engage the leading edge of the sheet and to clamp the same on said gripper stops, circumferential spacing members disposed at intervals along the length of the cylinder adapted to 30 hold the sheet in spaced relation with the periphery of said cylinder, a movable element adapted to project into the space between the sheet and the periphery of the cylinder and across the path of the sheet between several gripper stops and several spacing members and adapted to be engaged by the sheet to be moved thereby, tripping mechanism, means having operative connection with said tripping mechanism for 35 controlling the same, and means included in said last mentioned means and having operative connection with said movable element and adapted to be moved to render said controlling means ineffective to position said tripping mechanism to trip when said movable element is moved by the sheet. 40

9. In a printing press, the combination with a sheet carrying cylinder adapted to receive a sheet and to carry the same, circumferential spacing members disposed at intervals along the length of said cylinder adapted to hold the sheet in spaced relation with the periphery of said cylinder, means for holding the sheet on said cylinder, a 45 movable element extending across said spacing

members and adapted to project into the space between the sheet and the periphery of the cylinder and across the path of the sheet and having slots formed at the projecting portion thereof in registry with the several spacing members and adapted to be engaged by the sheet and to be moved thereby, tripping mechanism, means having operative connection with said tripping mechanism for controlling the same, and means included in said last mentioned means and having operative connection with said movable element and adapted to be moved to render said controlling means ineffective to position said tripping mechanism to trip when said movable element is moved by the sheet. 70 75 80

10. In a printing press, the combination with a sheet carrying cylinder adapted to receive a sheet and to carry the same, circumferential spacing members disposed at intervals along the length of said cylinder adapted to hold the sheet in spaced relation with the periphery of said cylinder, spaced gripper stops on said cylinder adapted to position the leading edge of said sheet in spaced relation with the periphery of said cylinder, spaced grippers adapted to engage the leading edge of the sheet and to clamp the same on said gripper stops, said spacing members supporting the leading edge of the sheet between said gripper stops, a movable element extending across said spacing members and adapted to project into the space between the sheet and the periphery of the cylinder and across the path of the sheet and having slots formed at the projecting portion thereof in registry with the several spacing members and gripper stops and adapted to be engaged by the leading edge of the sheet to be moved thereby, tripping mechanism, means having operative connection with said tripping mechanism for controlling the same, and means included in said last mentioned means and having operative connection with said movable element and adapted to be moved to trip to render said controlling means ineffective to position said tripping mechanism to trip when said movable element is moved by the sheet. 90 95 100 105 110

11. In a printing press, the combination with a sheet carrying cylinder adapted to receive a sheet and to carry the same, circumferential spacing members disposed at intervals along the length of said cylinder adapted to hold the sheet in spaced relation with the periphery of said cylinder, means for holding the sheet on said cylinder, a movable element extending across said spacing members and adapted to project into the space between the sheet and the periphery of the cylinder and across the path of the sheet and having slots formed at the projecting portion thereof in registry with the several spacing members and adapted to be engaged by the sheet and 115 120 125 130

to be moved thereby, tripping mechanism, means having operative connection with said tripping mechanism for controlling the same, a coupler included in said last mentioned means and adapted to be moved to render said means inoperative to position said tripping mechanism to trip, and connecting means between said movable element and said coupler whereby said coupler is moved to render said controlling means ineffective to position said tripping mechanism to trip when said movable element is moved by the sheet.

12. In a printing press, the combination with a sheet carrying cylinder adapted to receive a sheet and to carry the same, circumferential spacing members disposed at intervals along the length of said cylinder adapted to hold the sheet in spaced relation with the periphery of said cylinder, spaced gripper stops on said cylinder adapted to position the leading edge of said sheet in spaced relation with the periphery of said cylinder, spaced grippers adapted to engage 25 the leading edge of the sheet and to clamp the same on said gripper stops, said spacing members supporting the leading edge of the sheet between said gripper stops, a movable element extending across said spacing 30 members and adapted to project into the space between the sheet and the periphery of the cylinder and across the path of the sheet and having slots formed at the projecting portion thereof in registry with the 35 several spacing members and gripper stops and adapted to be engaged by the leading edge of the sheet and to be moved thereby, tripping mechanism, means having operative connection with said tripping mechanism for controlling the same, and means 40 included in said last mentioned means and having operative connection with said movable element and adapted to be moved to render said controlling means ineffective to position said tripping mechanism to trip when said movable element is moved by the sheet.

13. In a printing press, the combination with a tripping mechanism, means in operative relation with said tripping mechanism for controlling the same, means in operative connection with said controlling means and engageable with a sheet fed to the press to render said controlling means ineffective to position said tripping mechanism to trip, means independent of said second mentioned means adapted to be moved to render said controlling means effective to trip and means having operative connection with said last mentioned means and adapted to be engaged with said second mentioned means to render the same ineffective to allow said controlling means to position said tripping

mechanism to trip when said last mentioned means is positioned in inoperative position. 65

14. In a printing press, the combination with a tripping mechanism, automatic means in operative relation with said tripping mechanism for controlling the same, means in operative connection with said automatic means and engageable with a sheet fed to the press to render said automatic means ineffective to position said tripping mechanism to trip, means independent of said second mentioned means adapted to 70 be moved to render said controlling means effective to trip and means having operative connection with said last mentioned means and adapted to be engaged with said second mentioned means to render the same ineffective to allow said controlling means to trip when said last mentioned means is in inoperative position. 75

15. In a printing press, the combination with a press driven element, of a second element normally inactive but adapted to be moved, a couple member movably mounted on one of said elements and adapted to be moved to engage the other element to establish an operable connection therebetween, automatic means for controlling said coupler, a second coupler movably mounted on one of said elements and adapted to be moved to engage the other element to establish an operable connection therebetween, means for positioning said second coupler, and means in operative connection with said second mentioned means and adapted to be moved to render said automatic means inoperative to engage said first coupler with said other element when said second coupler is in disengaged position. 85

16. In a printing press, the combination with a movable element adapted to project across the path, of a sheet fed to the press and adapted to be engaged by the sheet and to be moved thereby, of a pivoted arm normally inactive, a couple member pivoted on said lever, movable means adapted to be engaged by said couple member to establish operative connection between said arm and said movable means, an arm on said couple member, and means for positioning said couple member and having a pivotal connection with said second mentioned arm, said pivotal connection being disposed to lie substantially coaxial of said pivoted arm when said coupler is positioned to engage said movable means. 105

17. In a printing press, the combination with a movable element adapted to project across the path of a sheet fed to the press and adapted to be engaged by the sheet and to be moved thereby, of a pivoted arm normally inactive, a couple member pivoted on

said lever, and a pivoted lever having the same axis as said pivoted arm and adapted to be engaged by said couple member to establish operable connection between said 5 arm and said pivoted lever, an arm on said couple member and means for positioning said couple member and having a pivotal connection with said second mentioned arm,

said pivotal connection being disposed to lie substantially coaxial with the axis of said 10 pivoted arm when said coupler is positioned to engage said pivoted lever.

In testimony whereof I affix my signature this 27th day of November, A. D. 1917.

ROBERT MIEHLE.
